UNITED STATES PATENT OFFICE.

JOHN B. SPERRY, OF AURORA, ILLINOIS, ASSIGNOR TO THE AMERICAN WELL WORKS,
OF AURORA, ILLINOIS, A CORPORATION OF ILLINOIS.

CENTRIFUGAL PUMP.

1,234,948.

Specification of Letters Patent. Patented July 31, 1917.

Application filed September 13, 1915. Serial No. 50,378.

To all whom it may concern:

Be it known that I, JOHN B. SPERRY, a citizen of the United States, residing at Aurora, in the county of Kane, State of Illinois, have invented certain new and useful Improvements in Centrifugal Pumps, of which the following is a specification, reference being had to the accompanying drawings.

My invention relates to centrifugal pumps and particularly to a new and improved form of liquid balancing means adapted to take up the end thrust of the shaft upon which the runners are mounted, and also to substantially balance the weight of the line of shafting when used in connection with a vertical deep well pump. My invention relates further to a new and improved form of casing for a pump of this type in which one side portion is adapted to be readily removed to afford access to the interior of the pump without disturbing the operative elements thereof. It is another object of my invention to improve pumping devices of this type in sundry details hereinafter pointed out. The preferred means by which I have accomplished my several objects are illustrated in the accompanying drawings and are hereinafter specifically described.

That which I believe to be new and desire to cover by this application is set forth in the accompanying claims.

In the drawings:—

Figure 1 is a central vertical section through the upper portion of a pump embodying my improvements;

Fig. 2 is a downward continuation of the parts shown in Fig. 1, being also a central vertical section;

Fig. 3 is a side view as seen from the right in Fig. 1 of the portion of the casing in which the upper set of runners and the fluid balancing means are located;

Fig. 4 is a central vertical section showing the pumping mechanism located preferably below the normal level of the water in the well;

Fig. 5 is a central vertical section through my improved fluid balancing means; and

Fig. 6 is a top view of the parts shown in Fig. 5, partly in section, being taken on line 6—6 of Fig. 5.

Referring to the several figures of the drawings in which corresponding parts are

indicated by the same reference characters,—

10—11 indicate heavy channel irons connected across the upper end of a well pit 12 supporting in position a base-plate 13 upon which is mounted an electric motor or other suitable driving device 14. The vertical pump shaft 15 which is connected to the motor 14 by means of a coupling device 16 of any suitable type is provided with an anti-friction bearing 17 of any suitable type 65 adapted to be cooled by a supply of water entering through a pipe 18 and passing out through a pipe 19. The shaft 15 is also provided with an end-thrust anti-friction bearing 20 of any suitable type which is 70 adapted to be cooled by the supply of water passing through the pipe 19 from the anti-friction bearing 17, such supply of water being adapted to be carried away by a pipe 21. The anti-friction bearing 17 is supported by 75 the base-plate 13, while the thrust bearing 20 is supported by a transverse plate 22, which, in the construction shown, is formed integrally with a casing 23 supported by the base-plate 13. The casing 23 is closed at its 80 lower end by a transverse plate 24 which is provided with a stuffing box 25 provided with packings 26—27 on opposite sides of a lantern-ring 28, the packings 26—27 being adapted to be suitably compressed by a 85 gland 29.

Secured to the lower end of the casing 23 is a shell member 30, which, together with a complementary shell member 31 (see Fig. 3) makes up the casing for the upper pumping units and for the liquid balancing means. To the lower ends of the shell members 30—31 is attached a collar 32 in which there is secured by means of screw-threads the upper end of a water discharge pipe 33. Between the casing 23 and the shell members 30—31 and between the collar 32 and said shell members are provided suitable packing rings 34 by which a tight joint may be procured. In order to render the shell member 31 readily removable without disturbing the packing rings 34, the upper and lower bearing edges are beveled as shown in Fig. 1 whereby the shell member 31 can be readily moved to the left in Fig. 3 when access is desired to the interior of the casing of the upper pumping elements and the liquid balancing means. As is clearly shown

in Fig. 1, the fixed shell portion 30 is provided with a suitable hand-opening adapted to be closed by a cover plate 35 removably secured in position, the removal of the small plate 35 sometimes being sufficient for the desired access to the fluid balancing means without the removal of the entire shell member 31.

As is shown at the bottom of Fig. 1, the lower edges of the shell members 30-31 and the upper edge of the collar 32 are rabbeted out for the reception of a spider 36 which serves to center in position a bearing member 37 for the shaft 15, a sand-collar 38 of any suitable type being mounted above the bushing 39 of said bearing to prevent the entrance of sand or grit between such bushing and the shaft 15. The bearing member 37 is provided with screw-threads a short distance below the spider 36 for connection thereto of the upper end of the shaft protecting casing 40. As is clearly shown at the top of Fig. 2, the shaft protecting casing 40 is perforated near its upper end, the perforations being covered by a suitable screen or filter 41 preferably in the form of a fine wire netting which serves to prevent the passage of sand or grit through the perforations. As is shown in Fig. 2, the pump shaft 15 is formed in sections joined together by suitable coupling sleeves 42 of any approved type. The shaft protecting casing 40 and the water discharge pipe 33 are also formed in sections joined together by a suitable coupling means as shown in Fig. 2. As therein shown, this coupling means comprises a bearing hub 43 for the shaft 15 provided with a bushing 44 of brass, wood, babbitt, or other suitable material. The ends of the shaft protecting casing 40 are connected to the bearing member 43 by means of screw-threads. A spacing ring 45 is connected to the bearing member 43 by means of webs 46, such spacing ring being adapted to be secured between the adjacent ends of the discharge pipe sections 33. The ends of the sections 33 are connected together on opposite sides of the spacing ring 45 by means of collars 47 secured by means of screw-threads 50 therein, such collars being connected together by any suitable means not shown. The well tube, down through which the shaft casing and the water discharge pipe extend, is indicated by the numeral 48, such well tube being formed in sections connected together by any suitable means, as is well understood in the art. The lower end of the water discharge pipe 33 is connected by means of a collar 49 with a sleeve 50, the lower end of which in turn is connected by any suitable means with a shell 51 through which the water is adapted to rise to the water discharge pipe 33 from the runners 52 mounted upon the shaft 15 in the pump casings 53 connected in series therebelow. The

lower end of the shaft protecting casing 40 is connected to a suitable sleeve 54 projecting upward from the shell 51, a bearing bushing 55 being provided at the lower end of the casing 40. Above the uppermost runner 52 in a suitable socket in the shell 51 about the shaft 15 is mounted a suitable packing 56 adapted to be appropriately compressed by a gland 57. The shell 51 is provided at opposite sides with radially extending webs 58 in which are provided ports 59 leading from the shaft 15 above the packing 56 to the exterior of the shell 51. Below the lowermost pump casing 53 is connected a casing 60 supporting a bearing member 61 for the lower end of the shaft 15. The bearing member 61 is in the form of a housing, the upper end of which is provided with a suitable packing 62 adapted to be compressed by a gland 63 above which is mounted about the shaft 15 a sand excluding collar 64. In the lower end of the housing 61 is mounted a downwardly-opening valve 61a. To the lower end of the casing 60 is connected in any suitable manner the upper end of a tail-pipe 65 adapted preferably to extend down into the well below the suctional influence of the runners 52.

My improved pumping apparatus comprises suitable runners 66-67 connected with the shaft 15 so as to be rotated thereby in the pump casing provided by the shell members 30-31, such runners being adapted to force the water out through a discharge pipe 68. As is best shown in Fig. 1, the pipe 18 which supplies water to the anti-friction bearings 17 and 20 is connected with the interior of the pump casing adjacent to the runner 66 in suitable position to receive a supply of water therefrom. Upon the operation of the pump, by reason of the rotation of the shaft 15 water will be forced upward through the water discharge pipe 33 by the runners 52 to the runners 66-67 by which the water will be forced to such additional height or distance as is desired.

My improved liquid-balancing means comprises in the construction shown a casting 68 having a suitable circumferential groove adapted to fit upon flanges 69-70 extending inward from the upper ends of plates 71-72 carried by the shell members 30-31, respectively, for closing the casing about the shaft 15 above the runners 66-67. Pins 73 are provided at diametrically-opposite points 120 for holding the casting 68 against rotation relative to the shell members 30-31. As is best shown in Fig. 5, the casting 68 comprises a hollow plate portion 74 reinforced by radially-extending ribs 75 and a hollow sleeve portion 76 whereby clear water under pressure delivered through a pipe 77 to an inlet nozzle 78 is adapted to apply pressure at the lower end of the hollow sleeve portion 76 at all points thereabout, as will be

readily understood. Loosely mounted within the sleeve portion 76 of the casting 68 is a sleeve portion 79 of a second casting, a plate portion 80 of which extends substantially parallel with the plate portion 74 of the casting 68. A collar 81 is mounted by means of screw-threads upon the lower end of the sleeve 79 adapted to be adjusted as desired thereon, being held in adjusted position by means of a pin 82 secured by means of screw-threads in a suitable socket between the collar 81 and the sleeve 79. The plate 80 is adapted to contact at its outer edge a suitable bearing portion of the plate portion 74 of the casting 68, and the collar 81 is adapted to contact suitable bearing portions formed upon the lower end of the sleeve 76 on both the inner and outer edges thereof on opposite sides of the annular chamber in such sleeve. The sleeve 81 may, of course, be adjusted so as to provide any desired aggregate play between the bearing portions of the casting 68 and the adjacent bearing portions of the plate 80 and the collar 81. The casting comprising the sleeve 79 and the plate 80 is adapted to be secured to the shaft 15 and to be adjusted relative thereto by reason of being secured by means of screw-threads upon a sleeve 83 which is keyed against movement relative to the shaft 15. The sleeve 79 and plate 80 are held in adjusted position relative to the sleeve 83 and the shaft 15 by means of a collar 84 provided with pins 85 which are adapted to be adjusted as desired relative to openings 86 in the upper face of the plate 80. The collar 84 and the upper end of the sleeve 83 are angular in shape whereby one of such members is held against rotation relative to the other, but the collar 84 is adapted to be raised readily along the sleeve 83. Whenever it is desired to adjust the plate 80 relative to the shaft 15, the collar 84 is elevated to free the pins 85 from the openings 86, whereupon the plate 80 may be turned by the application of a suitable wrench for raising or lowering the shaft 15 relative to the plate 80 and consequently relative to the casting 68 and the shell members 30-31. When the proper adjustment is secured, the collar 84 is lowered to bring the pins 85 again into position in the openings 86, whereupon the parts are held against further adjustment. When water is being supplied under pressure through the pipe 77 during the operation of the pump, this water applies downward pressure against the collar 81 as above explained, tending to force such collar and the shaft 15 downward. Pressure is then applied about the lower end of the sleeve 76 between such sleeve and the sleeve 79, and thence upon the lower face of the plate 80, tending to move the plate 80 and the shaft 15 upward. As is readily understood in the

art in connection with devices of this type, the alternate upward and downward pressures upon the connected parts comprising the collar 81, the sleeve 79, and the plate 80, serve to balance the weight of the shaft 15 and to practically support the shaft 15 upon a film of water being forced outward between the edge of the plate 80 and the bearing portion of the plate 74. A portion of the water through which downward pressure is applied upon the upper face of the collar 81 escapes between such collar and the outer edge of the sleeve 76 against the pressure of the water being forced outward by the runner 67. The escape of this film of water prevents the entrance of the water being pumped and thus keeps the water-balancing means free of the sand and grit carried by the water being pumped. The water escaping between the outer edge of the plate 80 and the bearing portion of the plate 74 is free to pass through a pipe 87 to the pump casing below the runners 66-67.

As is shown in Fig. 1, a pipe 88 connects with the pipe 77 through which clear water from a separate source is delivered under pressure, such pipe 88 branching at the coupling 89 into two leads 90 and 91 provided with gate-valves 92-93, respectively, by the use of which they may be closed against the passage of water if desired. The pipe 90 passes through the wall of the shell member 30 and connects with the upper end of a duct 94 leading vertically through the bearing member 37 to the interior of the shaft 100 protecting casing 40. The pipe 91 extends downward through the well tube 48 adjacent to the water-discharge pipe 33, being supported at intervals by the coupling devices 47, being connected at its lower end with a duct 95 leading through the casing members 53 at one side, and through a portion of the casing member 60, leading to the shaft 15 below the packing 62 in the housing 61.

By opening the valves 92-93 before the operation of the pump is started, the pipes 90-91, the shaft protecting casing 40, and the housing 61, are all adapted to be filled with clean water under pressure from the pipe 88, the water passing into the upper end of the shaft protecting casing 40 being adapted to pass down between the shaft 15 and the bearing bushings 44 for filling the lower sections of the casing 40. The shaft 15 is thus lubricated ready for operation. After the pump has been started the valve 92 may be closed if desired, a sufficient amount of water being taken into the shaft protecting casing 40 through the wire netting 41 for the purpose of suitably lubricating the shaft bearings above the runners 52. Whether the shaft casing 40 is supplied only through the perforations in its upper end, or both through such perforations and through the pipe 91, such water is adapted

to work its way along the shaft 15 to the ports 59 and thence out into the well tube 48. In case a portion of the water being pumped forces its way upward from the 5 runner 52 through the packing 56 carrying with it a small quantity of sand or other grit, such water is effectively prevented from entering the bearing 55 against the pressure of the water coming downward therethrough 10 by reason of the free escape open to the water through the ports 59. The water entering the housing 61 through the pipe 91 is preferably delivered thereto at a greater pressure than that of the water being 15 pumped. The water being pumped is therefore prevented from entering the housing 61 through the packing 62 into contact with the bearing bushing 96. It will be understood that by a partial closing of the valves 20 92 and 93 the supply of water to the pipes 90—91, respectively, may be controlled so as to control to some extent the pressure in the housing 61 and in the shaft casing 40.

While I prefer to use clear water in connection with the liquid balancing means, it 25 will be understood that I do not restrict myself in this particular except as herein-after specifically claimed inasmuch as any suitable fluid under pressure may be used 30 quite independently of the character of the liquid being pumped. In case the pump is being used for raising water for domestic uses, it is ordinarily preferable to use water for purposes of balancing and lubricating. 35 In case the pump is being used for raising water solely for irrigating, for example, it might be preferable to use oil both for lubricating and for balancing. In case the pump is being used for raising oil, it is 40 ordinarily preferable to use a supply of clean oil for lubricating and balancing. My claims are, therefore, to be construed to cover the structure shown quite regardless of the character of the liquid being pumped 45 or the character of the liquid supplied under pressure to the balancing means, except as such features are specifically set forth in the claims.

While I have shown only a single balancing mechanism, it will be understood that I do not wish to restrict myself in this particular, the size of the balancing means and the number of separate balancing mechanisms used being dependent upon the length 55 of the line of shafting, the rate of pumping, and other variant elements as is well understood in the art.

What I claim as my invention and desire to secure by Letters Patent, is—

60 1. In a pump, the combination of a pump casing member adapted to support the pumping mechanism, a second casing member, and means for removably connecting said second casing member with said first-named casing member, the upper and lower

edges of said second casing member being beveled whereby it can be removed readily without disturbing the adjacent parts.

2. In a pump, the combination of a casing having a beveled lower edge, a pump casing member in the form of a shell affixed to said first-named casing, a second pump casing member in the form of a shell having its upper edge beveled to correspond with the shape of the lower edge of said first-named casing, a packing interposed between the beveled portions of said two casings, and means for removably connecting said second-named shell member to said first-named casing.

3. In a pump, the combination of a casing having a beveled lower edge, two casing members in the form of shells having their upper edges beveled to correspond with the shape of the lower edge of said first-named casing, a packing interposed between said first-named casing and said shell members, and means for removably connecting one of said shell members with said casing and with the other shell member.

4. In a pump, the combination of a casing, comprising a removable shell member having its upper and its lower edges beveled, packings interposed between the beveled edges of said shell member and the adjacent edges of the remaining portion of the casing, and means for removably connecting said shell member in position.

5. In a pump, the combination of a shaft, rotary pumping means mounted on said shaft, and a casing the portion of which extending longitudinally of said shaft for inclosing said rotary pumping means is formed of two shell members one of which is removable for access to the rotary pumping means, the upper and lower edges of the removable shell member being beveled whereby said shell member may be readily removed without disturbing the packings adjacent thereto.

6. In a pump, the combination of a shaft, rotary pumping means mounted on said shaft, and a casing the portion of which extending longitudinally of said shaft for inclosing said rotary pumping means is formed of two shell members in one of which the operative parts are mounted and the other of which is removable for access to such operative parts, the upper and lower edges of the removable shell member being beveled whereby it may be readily removed without disturbing the packings adjacent thereto.

7. In a fluid balancing means, the combination of a fixed member having an annular chamber formed in one end thereof, means for delivering fluid under pressure to said chamber, a shaft extending through said fixed member, a plate connected to said shaft extending over the end of said annu-

lar chamber, and a second plate connected to said shaft adapted to contact the opposite end of said fixed member and adapted to trap the fluid under pressure passing from 5 said first-named plate along said shaft to said second plate, the shaft and said two plates being adapted to have a slight movement relative to said fixed member whereby the pressure is alternately relieved at said

10 two plates.

8. In a fluid balancing means, the combination of a fixed sleeve having an annular chamber formed in one end thereof, a second sleeve extending loosely through said 15 fixed sleeve, a plate carried by said second sleeve extending over the end of said annular chamber, a second plate carried by said second sleeve adapted at its outer edge to contact the opposite end of said fixed sleeve, 20 and means for delivering fluid under pressure to said annular chamber.

9. In a fluid balancing means, the combination with a fixed sleeve, and a plate formed integrally therewith, said sleeve and 25 plate being hollowed out so as to provide an annular chamber in the end of said sleeve, of means for delivering fluid under pressure to said chamber, a shaft extending through 30 said sleeve, and plates carried by said shaft opposite respectively the end of said sleeve and the plate formed integrally with said sleeve, said last-named plates being adapted to have a limited play toward and from said 35 integral sleeve and plate whereby the pressure is alternately relieved opposite said two plates.

10. In a pump, the combination of a pump casing, a shaft extending into said casing, a runner in said casing adapted to 40 be driven by said shaft for forcing water through said casing, and balancing means connected with said shaft serving to close one end of said casing about said shaft, said 45 balancing means comprising a plate connected with said shaft inside of said casing, a second plate connected with said shaft out-

side of said casing, a fixed member having bearing portions with which said plates are adapted to contact alternately as said shaft moves longitudinally, and means for delivering fluid under pressure to said fixed member whereby the water pumped is prevented from escaping from the casing between said fixed member and said first-named plate.

50

55

11. In a pump, the combination of a pump casing, a shaft extending into said casing, a runner in said casing adapted to be driven by said shaft for forcing water through said casing, and balancing means 60 connected with said shaft serving to close one end of said casing about said shaft, said balancing means comprising a fixed sleeve provided with an annular chamber in its end, a plate connected with said shaft inside 65 of said casing adapted to close said annular chamber, and means for delivering fluid under pressure to said annular chamber whereby the water pumped is prevented from escaping from said casing between said plate 70 and the end of said sleeve.

12. In a pump, the combination of a pump casing, a shaft extending into said casing; a runner in said casing adapted to be driven by said shaft for forcing water 75 through said casing, and balancing means connected with said shaft serving to close one end of said casing about said shaft, said balancing means comprising a plate connected with said shaft inside of said casing, 80 a second plate connected with said shaft outside of said casing, a fixed member having bearing portions with which said plates are adapted to contact alternately as said shaft moves longitudinally of itself in opposite 85 directions, and means for delivering fluid under pressure to said fixed member whereby the fluid under pressure is adapted to escape from said fixed member into said casing against the pressure of the water 90 pumped.

JOHN B. SPERRY.
